VENTILATED SHIPPING CONTAINER

Harold A. Simms, Redondo Beach, Calif., assignor
to The Patent and Licensing Corporation, New
York, N. Y., a corporation of Massachusetts

Application June 7, 1946, Serial No. 675,095

1 Claim. (Cl. 229—6)

1

This invention relates to ventilated shipping containers of the type in which baby chicks and the like are transported, and is more particularly concerned with such containers made of corrugated fiberboard or similar strong lightweight, foldable sheet material.

Generally, the present invention contemplates improvements in certain details of construction and combinations tending to increase the general efficiency and desirability of chick shipping boxes of the type set up for use from flat foldable sheets, without the aid of staples, tape, glue or other such fastening means.

Other objects of the present invention, including specific features and advantages, will become more readily apparent in the following description and the accompanying drawings in which—

Fig. 1 is a perspective view of a completely erected chick box embodying features of the present invention;

Fig. 2 is a view similar to Fig. 1 with the cover lifted from the box in order to expose details of the interior construction;

Fig. 3 is a vertical section taken substantially along lines 3—3 of Fig. 1;

Fig. 4 is a vertical section taken substantially along lines 4—4 of Fig. 1 and Fig. 3, one of the upwardly opening, hinged cover sections being shown in phantom to better illustrate the manner in which the cover sections may be independently released and secured to the box body; and

Fig. 5 is a plan view of the blank forming the body of the present chick shipping container.

Referring now specifically to Fig. 5 of the drawings, there is illustrated a substantially rectangular flat blank, designated generally by the reference numeral 10, which has been stamped, scored and cut out, as indicated, in order to fabricate the body of a chick box embodying features of the present invention. This body blank may be formed from flat sheets of corrugated fiberboard, solid fiberboard or other similar foldable material which is lightweight, yet possesses adequate flexibility and strength for purposes of the present invention.

As shown in Fig. 5, the body blank 10 has a substantially rectangular bottom 11, end-wall portions 12 and side-wall portions 13, all flexibly connected together to fold along score lines 14 and 15 and thus form a box body with a bottom, and upright side and end-walls. The transverse fold lines 14, extending along the opposite side margins of the bottom 11 of the blank, intersect the longitudinal fold lines 15, extending along the opposite end margins of the bottom. Beyond

the points of intersection, and colinear with the fold lines 14, the blank is cut, as indicated at 16, to separate the side-wall portions 13 from the end-wall portions 12. The longitudinal fold lines 15 are extended fully beyond their intersection with the transverse fold lines, as indicated at 17, to thus provide hinged flaps 18 integral with the side-wall portions 13 and adapted to be interlocked with the end-wall portions 12, as will be described in detail hereinafter.

Adjacent the longitudinal edge of each of the end-wall portions 12, a scored fold line 19 is formed which extends substantially parallel to the fold line 15 and provides a relatively narrow hinged flap 20. The fold lines 19 are interrupted at two spaced points intermediate their ends by substantially shallow, U-shaped slits, as at 21. In setting up the box body, the flaps 20 will be bent slightly inwardly toward each other to thus present pairs of slots 21 along the upper margin of each of the end-walls.

The upper edges of the side-walls 13 are formed with semi-hexagonal riser sections to thus provide elevated portions 22 spaced from each other by a depressed mid-portion 23 complementary in configuration to the elevated portions.

In each of the respective end-wall and side-wall portions there is provided a substantially H-shaped cut forming a slot 24 which is positioned 30 medially of the length of each such wall portion and intermediate the upper and lower margins, the opposite slots of each pair being in alignment. These slots receive and disengageably lock in place the saber end tabs of partition pieces which are located within the erected box body, as will be more fully set forth hereinafter.

The box body is rapidly and efficiently erected from the flat blank 10 by bending the end-walls and side-walls substantially at right angles to the bottom and folding the locking flaps 18 inwardly along fold lines 17 to lie interiorly of the end-walls. Ears 18', formed on each of the flaps, are inserted upwardly through the slots 21. Thus, there is assured a rigid and secure body having 45 reinforced corners frictionally locked against accidental disengagement by the aforescribed simple locking device which renders unnecessary all stitching, tape, glue or other such fastening means.

It is to be noted that in the erected box body, the horizontal upper edges of semi-hexagonal riser sections of the side-walls extend in a plane somewhat higher than the plane of the upper edges of the end-walls, this being particularly 50 noticeable after the relatively narrow upper flaps

28 have been bent slightly inwardly, as previously indicated, to provide the slots for corner locking purposes.

A transverse partition 25 is inserted in the receptacle and extends between the opposite end walls 12 with which it is securely locked against accidental disengagement. To this end, saber end tabs 26 are provided on the transverse partition for rapid and easy insertion through the opposite companion H-shaped slots 24. As shown particularly in Figs. 1 and 4, these opposite saber end tabs project outwardly beyond the outer end-walls and are frictionally retained in such position by the resilient portions of the H-shaped slot. The upper edge of the transverse partition is provided with semi-hexagonal riser sections 27 conforming substantially to the riser sections 22 of the side walls 13. Intermediate these riser sections there may be provided arcuately formed ears 28 at a somewhat lower level than the riser sections 27, these ears being joined together at a still lower level by a substantially horizontal edge, as shown at 29 in Fig. 2.

A longitudinal partition 30 is next interfitted with the transverse partition 25 in the usual manner, as by means of vertical slots 31 and 32 provided respectively along the center of the partitions 25 and 30 and extending from their opposite edges, as shown in Figs. 2, 3 and 4, substantially to their respective mid-points. The partition 30 is also provided with saber end tabs 33 which are projected through the associated H-shaped slots 24 to frictionally lock said partition in upright position in the manner previously described in connection with transverse partition 25.

The upper edge of the longitudinal partition 30 is formed with three upstanding locking ears 35, the center ear being located substantially at the mid-point of the partition and the other two ears each nearer an end of the partition and preferably spaced equi-distant from the center ear. As best shown in Figs. 2 and 3, these ears are each provided with a slight undercut notch or recess 36, at least as wide as the thickness of the sheet material, and located, in each instance, on the same side of the ear and preferably at the juncture of the ears and the upper straight edge of the partition.

The cover for the chick box of the present invention is fabricated from flat sheet material similar to that used for the other members described above. As illustrated in Figs. 1, 2 and 4, the cover 40 is made from a blank which is stamped out and creased or scored along six parallel longitudinal lines. As seen in Fig. 2, a pair of longitudinally extending scores or creases 46a are formed on the upper surface of the cover along lines equi-spaced from the longitudinal center line of the cover, these scores or creases being spaced from one another a distance equal to the length of the depressed mid-portions 23 formed on the side-walls of the box. Longitudinally extending pairs of crease or score lines 46b are formed on the bottom surface of the cover, the score lines of each of these pairs being spaced apart a distance equal to the length of the upper horizontal edges of the riser sections 22 on the side walls, and being located so as to coincide with the ends of those edges, respectively, when the cover is inserted over the box body. When the cover is bent upwardly along creases 46a and downwardly along creases 46b, it conforms in vertical section to the semi-hexagonal riser sections and depressed mid-portion of the side-walls 13 and transverse partition 25.

The depressed flat mid-portion 41 of the cover is provided with three aligned slots 42 located substantially medially thereof. These slots are of a length and width to accommodate with ease the upstanding ears 35 on the longitudinal partition 30. A pair of aligned slots 43 are provided in the cover substantially along the transverse median line thereof, these transverse slots being located on opposite sides of the central longitudinal slot 42 partly along the depressed mid-section 41 and partly along the inclines of the riser sections adjacent to said depressed section. These transverse slots are of such a length and width and are so located as to permit the entrance therethrough of the arcuate ears 28 located on the transverse partition 25, the reception of these ears through said slots serving to further reinforce said partition in its upright position and being accomplished at the time the cover member 40 is first engaged with the partitions and body of the set-up container.

In the practice of the present invention, the cover is directed into position on the container body so that the ears 28 may be received through the slots 43 and, simultaneously therewith, the recessed ears 35 may be received through the longitudinal slots 42. In this first assembled position, the cover, being in substantial conformity with the semi-hexagonal riser sections of the side-walls and transverse partition, as previously described, will rest on these members and be likewise reinforced thereby, with the depressed central portion 41 of the cover resting on the flat upper edge of the longitudinal partition 30. The cover is then prevented from being accidentally disengaged by sliding it along the longitudinal partition until the ends of the slots 42 abut against the inner edges of the undercut notches 36, as best indicated at 45 in Fig. 1. After the cover has thus been locked with the recesses 36 of the tab 35, the articulated cover sections 46 and 47 may be closed and secured to the body by means of the spaced tuck flaps 48 and 49 located respectively on the opposite longitudinally bent end flanges 50 and 51.

These tuck flaps 48 and 49 are so located with respect to the body slots 21 so as to be slightly offset with respect to the slots when the cover is not in interlocked relation to the partition 30, but in alignment with the slots for ready insertion within the latter only after the cover has been slidably locked in engagement with the notched ears 35. The width of the slots 21 is preferably such as just barely to accommodate two thicknesses of the corrugated fiberboard or other sheet material used in forming the blanks, the two thicknesses being provided by the upwardly extending ears 18' of the hinged corner flaps 18 and the downwardly extending cover flaps 48 and 49. In order to facilitate reception of the flaps 48 and 49 within the slots 21, the edges of the flaps may be beveled off, as at 48a (and 49a, not shown) respectively. Locking notches 48b (and 49b, not shown) are formed at each side of the flaps 48 and 49 at the junctures thereof with the flanges 50, 51, respectively.

As is readily apparent, each articulated section 46 and 47 of the cover member is adapted to be opened upwardly and each manipulated independently to open or close half of the container at a time. As shown particularly in Figs. 1 and 3, the cover extends beyond the side-walls 13 a distance approximately equal to the extent to which the end saber tabs 33 of the longitudinal partition 30 project therebeyond. There is thus

not only afforded means for preventing injury to these saber tabs and for preventing the cutting off of the circulation of air from the exterior to the interior of the container, but also there is provided a convenient and safe means for lifting the closed container by the cover, so long as the latter is in locked position with respect to the container body by engagement of the slots 42 with notches 36. It is to be noted that the hinged flaps 20 and the flanges 50 of the cover are each sufficiently wide so that a complete closure for the container is provided through the overlapping of the flaps 20 by the flanges 50.

Ventilating holes 60 are provided at suitable intervals, as shown, in the walls of the body and in the riser sections of the cover to provide adequate circulation and ventilation for the chicks being shipped therein regardless of how the containers are stacked during storage and shipment. The punch-outs for the vent holes may be cut through but allowed to remain in the hole to be easily punched out by the shipper to provide proper ventilation, depending on the temperature conditions under which the chicks are shipped. The provision of ventilation openings 60 in the riser sections of the cover is particularly important, as these openings permit adequate circulation of air within the interior of the container during storage and shipment, when these containers are piled on top of each other. Furthermore, it is to be noted that the relatively wide, flat bearing surfaces provided by the elevated semi-hexagonal riser sections of the cover will sustain such compression loading with substantially no danger that the piles will be unsteady or the superposed containers totter or slide relative to one another and frighten or otherwise cause injury to the contents. Even in the event of such sliding or other relative displacement of the superposed containers, the projection of the longitudinal locking ears 35 and of the transverse ears 28 above the depressed surface of the cover serves to prevent such containers from sliding into a position which would effectively reduce or cut off entirely the circulation of air through the ventilation openings in the riser sections of the cover, and thus create dead air pockets so lethal to the objects being shipped.

Although the container has herein been referred to more particularly as a chick box, it will be understood that this designation has been em-

ployed for simplicity of description and not for the purpose of limiting the use of the container. Accordingly, the term "chick box" in the claim is to be understood as including a container for shipping chicks or other poultry.

I claim:

A chick box of foldable sheet material comprising a body having a rectangular bottom, side and end-walls flexibly connected together, said end-walls having slots near each end adjacent the upper edge thereof, said side-walls having integral corner flaps at each end thereof, and the upper edges of said side walls being formed with semi-hexagonal riser sections, said flaps having locking tabs for insertion in said slots to connect the side-walls with the end-walls, a partition extending longitudinally along the median line of said container and disengageably connected to said side-walls, and a cover comprising a single blank bent to form a flat mid-section and articulated end sections opening upwardly independently of one another along score lines spaced laterally from said partition, said cover being adapted to be interlocked with said partition by longitudinal sliding movement, each of the articulated sections of the cover having spaced flaps along each of its ends slightly offset with respect to said slots when the cover is not in interlocked engagement with said partition but in alignment with and readily insertable in said slots after said cover has been slidably interlocked with said partition whereby to hold said cover sections in closed position and said cover being provided with vent holes and conforming in vertical section to said upper edges of said side-walls thereby providing the top of the box with flat bearing surfaces capable of sustaining compression loading of superposed boxes while permitting ventilation of the interior of said box through vent holes.
